W. D. KURZ

FUSE PULLER AND REPLACER

Filed April 13, 1922

UNITED STATES PATENT OFFICE.

WILLIAM D. KURZ, OF APPLETON, WISCONSIN.

FUSE PULLER AND REPLACER.

Application filed April 13, 1922. Serial No. 552,300.

To all whom it may concern:

Be it known that I, WILLIAM D. KURZ, a citizen of the United States, residing at Appleton, in the county of Outagamie and State of Wisconsin, have invented a new and useful Fuse Puller and Replacer, of which the following is a specification.

The object of my invention is to provide a novel tool adapted to operate on all standard size fuses; to provide a tube that is convenient for electricians to carry, and to provide a tool made of novel material, and for other purposes, as more fully hereinafter set forth. I attain the objects of my invention by the device illustrated in the accompanying drawings, in which—

Figure 1 is a side elevation of the invention;

Fig. 2 is an edge elevation;
20 Fig. 3 is a section on line 3—3 of Fig. 1; and
Fig. 4 is a cross section on line 4—4 of Fig. 2.

Like numerals indicate like parts in each 25 of the several views.

Referring to the accompanying drawings, I provide like plier members 1 and 2 pivoted approximately near the center of same by a suitable pivot hinge member 3. Near 30 one end of the respective plier members I provide the opposite concave portions 4 and the opposite smaller concave portions 5, said latter concave portions being positioned in the tapered end portions 8 of the pliers as shown in Figs. 2 and 3. I further provide a series of spaced opposite grooves 7 in the small end of the pliers for holding wires tight when making joints on live wires, so that the operator is thoroughly insulated. 35

40 At the opposite end of the tool I provide the opposite concave portions 6. A novel feature of my device is the provision of the rounded inside edges 9 to prevent pinching of the fingers should the pliers slip off the fuse and allow the portion of the pliers grasped in the hand to close suddenly. As indicated in Figs. 3 and 4 of the drawings, the pliers are made of high insulating material, the preferred material being vulcanized fiber that is non-breakable.

The tool has been tested as safe to handle 4,000 volts. It will take in all standard-sized no-arc fuses that are made. That is, one end takes in from 10 ampere to 100 am-

pere fuses; and the other end takes in from 55 150 to 600 ampere fuses. An efficient joint is provided at the pivoting or hinging the plier members to each other, as shown in Figs. 1 and 3. The tool is of a shape that permits of its being conveniently carried by 60 electricians in the pocket, and the rounded edges 9 protect the fingers from being pinched in the event that the tool slips off the work being held. All edges of the tool except the actual fuse-gripping portions are 65 rounded. The end groove on the small end is intended to remove fuses of the size of a lead pencil or to tighten or loosen knots on live work; also, to re-form fuse clips when they have become bent out of shape. 70

What I claim is:

1. In a fuse puller and replacer, like plier members of high insulating material, said plier members having a plurality of opposite concave portions at each end of the 75 pliers, said concave portions being of different sizes suitable for operating on all standard-sized fuses, and a plurality of spaced opposite grooves in the pliers of suitable size for holding wires when making 80 joints on live wires.

2. In a fuse puller and replacer, the combination of like plier members of high insulating material, the plier members having suitable opposite concave portions and 85 grooves for operating on various sizes of fuses, etc., and the handles on the opposite end of the pliers having their inner edge surfaces substantially rounded at the portion of the pliers gripped by the hand, 90 whereby to prevent pinching of the fingers if the portion of the plier held by the hand suddenly closes.

3. In a fuse puller and replacer, the combination of like plier members of high insulating material, a pivot securing said plier members in operative engagement, the pliers having opposite concave portions for grasping fuses, etc., one end of each of the plier members being similarly tapered, said end having opposite concave portions positioned within the tapered portion, whereby a relatively narrow operating portion will be provided on the pliers, whereby to extend its usefulness, substantially as hereinbefore 100 described.

WILLIAM D. KURZ.

Certificate of Correction.

It is hereby certified that in Letters Patent No. 1,481,517, granted January 22, 1924, upon the application of William D. Kurz, of Appleton, Wisconsin, for an improvement in "Fuse Pullers and Replacers," errors appear in the printed specification requiring correction as follows: Page 1, after line 71, insert the following as claim 1:

1. In a fuse puller and replacer, like plier members of high insulating material, said plier members having a plurality of opposite concave portions at each end of the pliers, said concave portions being of different sizes suitable for operating on all standard-sized fuses.;

lines 72 and 82, for the numerals of claims 1 and 2 read 2 and 3, respectively; strike out lines 94 to 106, comprising present claim 3; and that the said Letters Patent should be read with these corrections therein that the same may conform to the record of the case in the Patent Office.

Signed and sealed this 16th day of March, A. D. 1926.

[*SEAL.*]

M. J. MOORE,
Acting Commissioner of Patents.
